UNITED STATES PATENT OFFICE

2,087,433

AUTOMATIC OVEN LIGHTER FOR GAS STOVES

Peter I. Hollman, Rockford, Ill., assignor, by mesne assignments, to Reconstruction Finance Corporation, Chicago, Ill., a corporation of the United States

Application November 1, 1932, Serial No. 640,695

1 Claim. (Cl. 158—115)

This invention relates to ignition devices, and more particularly an automatic oven lighter for gas stoves, and is an improvement on that disclosed in the copending application of Frank A. 5 Gauger, Serial No. 608,713, filed May 2, 1932.

Gas ranges of the more recent designs have low ovens in which the oven burner is disposed at an appreciable distance below the cooking top, and, hence, considerably below the constantly 10 burning pilot light serving as the igniter for the oven burner, as well as for the cooking top burners. It has, therefore, been quite a problem to devise a practical form of flash-back tube to secure quick and positive automatic lighting, 15 despite the remoteness of the pilot light with respect to the burner, and the fact that the pilot light is so far above the burner. Successful functioning of a long range flash-back tube has been found to depend primarily on maintaining the 20 right proportion of gas to air, not allowing too much secondary air to mix with the gas admitted to the tube by the auxiliary pilot. The principal object of my invention is to provide a flash-back tube and auxiliary pilot housing constructed so as to secure such a balanced mixture 25 not only in lighting when the parts are cold, but in re-lighting when the parts are heated, whereby to secure good flame propagation from the main pilot back to the auxiliary pilot.

30 A special feature of the present invention is the provision of a flash-back tube of a certain sized cross-section, and an auxiliary pilot housing of larger cross-section and elongated sufficiently to accommodate a rather large jet—the 35 main jet of the auxiliary burner, for charging the flash-back tube.

Another feature is the provision of a secondary air injector between the auxiliary pilot housing and the flash-back tube for the purpose of 40 entraining cold air and accordingly moderating the draft effect in the tube by preventing overheating of the latter.

The invention is hereinafter fully described by reference to the accompanying drawings, where- 45 in—

Figure 1 is a view partly in elevation and partly in vertical section through a gas range equipped with an oven lighter made in accordance with my invention;

Fig. 2 is a vertical section through the oven lighter on a larger scale showing only the lower portion of the flash-back tube;

Fig. 3 is a section through the main pilot housing and showing the upper portion of the flash-back tube, and

Fig. 4 is a fragmentary section similar to Fig. 2 of a modified construction.

Similar reference numerals are applied to corresponding parts throughout the views.

Referring to Figs. 1, 2 and 3, the stove illus-

trated is of a low oven type, called a table-top range, having the usual cooking top 12 next to the oven section 13. The cooking top and the top of the oven section, it will be observed, are substantially at the same level, about table height. This accounts for the low elevation of the oven burner appearing at 14 with respect to the pilot light casing 15 of the automatic lighter 16 disposed in the center of the cooking top between the burners 17. The lighter 16 is of a well known type having flash-back tubes 18 radiating therefrom to conduct gas issuing from a port on any one of the cooking top burners to the lighter for ignition by the flame of the pilot burner 19 in the casing 15. The burner 19, for the sake of convenience, will hereinafter be referred to as the main pilot, although any type or kind of igniting device may be used in place of this main pilot. The usual gas supply manifold has the usual cocks thereon to supply gas to the various cooking top burners, and the main pilot 19 has a tube 22 connected with the manifold for supply of gas therefrom.

An oven cock also communicates with the manifold and delivers gas to the oven burner through an oven regulator 24 connected in any usual way between the oven cock and the pipe 25 extending down toward the mixer 26 of the oven burner. A tube 30 supplied with gas whenever the oven cock is opened serves to supply gas to a second pilot burner 31 for igniting the oven burner. The burner 31, for the sake of convenience and in order to distinguish from the main pilot 19, will be referred to hereinafter as the auxiliary pilot. It is also sometimes referred to as an "intermediate" burner for the reason that it is arranged to be automatically ignited similarly as one of the cooking top burners 17, and is arranged to light the oven burner. In other words, the oven burner is not ignited by direct flash-back thereto through a tube like one of the cooking top burners, but relies for its ignition upon the auxiliary pilot between the lighter 16 and the oven burner. The present invention has particular reference to the flash-back tube 32 and auxiliary pilot housing 33 disposed between the main pilot 19 and the auxiliary pilot 31, arranged to secure ignition of the latter from the former by flame propagation or "flash-back" through the tube.

The oven burner 14 has a lug 34 projecting therefrom provided with a projection 35 by means of which the same is arranged to be pinned in a slot 36 in a casting 37 fastened as at 38 to the wall of the oven. The casting 37 serves as a canopy or shield for the auxiliary pilot 31, which, as shown, projects through an opening in the oven wall and into the casting so that the inner end is disposed in close proximity to the bottom of the oven burner for good light-

ing. The auxiliary pilot 31 has a pad portion 39 provided thereon for abutment with the outside of the oven wall to permit fastening the same thereto by means of bolts 40 passed through the 5 pad portion 39 and oven wall and through a flange on the casting 31, abutting the inner surface of the same wall, as appears in Fig. 2. The interlocking of the oven burner 14 with the casting 37 and the fastening of the auxiliary pilot 31 to the 10 casting in the manner described, positively insures the proper relationship between the auxiliary pilot and the oven burner for good lighting. A mixer 41 is provided on the auxiliary pilot through which gas is delivered under pressure 15 from the tube 30, whereby to produce a Bunsen flame at the row of ports 42 provided in equally spaced relation lengthwise of the top of the auxiliary pilot burner. The ports 42 are all of a small size and spaced properly for good flame 20 propagation from the outer end of the burner to the inner end. At the outer end a large port 43 is provided centrally of the bottom of an upwardly projecting neck 44 cast integral with the burner. Openings 45 are provided in the side 25 walls of the collar for good aeration of the jet at the port 43. A large opening 46 is provided in the wall of the neck 44 on the inner side thereof for the purpose of propagating flame from the port 43 to the ports 42, certain ports 47 at the 30 outer end of the burner being advantageously located and inclined both for good flame propagation and to insure good heating of a bimetallic thermostat 48, which controls the opening and closing of a shut-off valve, not shown, interposed 35 between the supply pipe 25 and the mixer 26 of the oven burner.

The large main port 43 in the outer end of the auxiliary pilot burner 31 is the means for charging the flash-back tube 32, and it is at this point 40 that the auxiliary pilot is ignited when the flash-back occurs. I have found through experimenting that the quickest and most positive lighting depends upon a good flow of gas from this port, which naturally necessitates enlargement thereof 45 with relation to the size of the ports that are only to serve for chain lighting from one end of the burner to the other. I have also found that the enlargement of the main port should be to a certain extent proportionate to the remoteness of 50 the main pilot 19. The jet at this port will accordingly be quite large, and that accounts for the size of the housing 33 which, as shown, has the base portion 50 thereof fitting on the reduced upper end 51 of the collar 44. I prefer to have 55 the housing 33 large enough in diameter and long enough so that the jet does not come into contact with the walls of the housing. In that way there is no likelihood of any objectionable odor in operation. The flash-back tube 32 is smaller in 60 diameter than the housing 33, and has its lower end fitting in a neck 52 provided on the upper end of the housing. A bell-shaped enlarged portion 53 is formed on the upper end of the housing directly under the neck 52 and has a series of holes 65 54 opening into the bottom thereof around the outside of the upper end of the housing, whereby to form an injector to entrain air with the products of combustion from the main jet and accordingly moderate the heating of the flash-back tube 70 32 so that there will be no excessive draft. Such heating as the tube 32 may be subjected to while the main jet is burning is also bound to be dissipated soon after the auxiliary pilot burner is 75 extinguished, owing to the circulation of cold air through the tube 32 taken in through the holes

54 by reason of the draft effect in the tube. Consequently, there will be no difficulty in relighting the oven burner should the housewife want to do so soon after the oven burner has been turned off. The tube 32 has its upper end fitting in a neck 55 5 on the side of the housing 18 of the lighter 16, so that the combustible mixture discharged into the lower end of the tube from the port 43 is conducted through the tube to the main pilot 19 10 for ignition, whereupon a flash-back occurs 15 through the tube to ignite the auxiliary pilot 31, first at the port 43 and then by flame propagation to the ports 47 and ports 42. The tube 32 has one side wall thereof cut at points uniformly spaced lengthwise of the vertical portion of the 15 tube, as appears at 56, a portion of the wall below each cut being pressed in or indented whereby to provide atmospheric openings 57. This is to supply the necessary secondary air to the gas as it travels up to the main pilot 19, in order to 20 secure the correct proportions for flash propagation back to the auxiliary pilot 31. In other words, the secondary air taken in insures a proper balance between the gas delivered from the auxiliary pilot and the air mixed therewith in the 25 tube to secure immediate flash-back from the main pilot to the auxiliary pilot. The construction illustrated and just described has been found to give very good results with natural gas, which is admittedly the most difficult to handle so far as automatic flash-back lighting is concerned. Where manufactured gas is to be used, the housing for the main jet may take the form illustrated at 33' in Fig. 4. It will be observed that this 30 housing has no injector at the upper end thereof but is made simply large enough and long enough to accommodate the jet. I have found that regardless of the fact that the draft is not checked and no special effort is made to cool off the flash-back tube, there is no difficulty in relighting with 35 manufactured gas.

It should be understood that while housings 33 and 33' are shown as separate cast parts, these may be formed in one piece with the tubes 32, simply by enlargement of the end of the tube 45 in a manner thought to be self-evident, and the appended claim should be construed accordingly.

It is believed the foregoing description conveys a good understanding of the objects and advantages of my invention. The appended claim has been drawn with a view to covering all legitimate modifications and adaptations.

I claim:

In combination, a first gas burner, a second gas burner to be ignited from the first burner and located at a lower elevation, a flash-back tube disposed with its lower end adjacent the second burner and its upper end adjacent the first burner, the second burner having an enlarged port arranged to discharge gas into the flash-back tube, a substantially vertical housing of enlarged cross-section relative to the cross-section of the flash-back tube disposed over said port and communicating with the lower end of said tube, said housing being of sufficient dimensions to enclose a large jet which will project upwardly from said port when the gas issuing therefrom is ignited, and said housing having the upper end thereof enlarged to provide an injector which is largest at its lower end and communicates at its smaller upper end with the flash-back tube, the lower end of said injector having one or more air inlet openings provided in the bottom thereof.
